Oct. 25, 2007.

CLAIM

(51) **LOC (9) Cl.** **08-05**

The ornamental design for an arm for an actuatable holding
system, as shown and described.

(52) **U.S. Cl.** **D8/373**

DESCRIPTION

(58) **Field of Classification Search** D8/354,
D8/373; 248/231.51, 316.5; 211/70.6; 24/598.5;
D6/547, 552

See application file for complete search history.

FIG. 1 is a lower-front perspective view of the ornamental
design for an entire configuration for an actuatable holding
system according to the invention, with the arms shown in a
closed position.

FIG. 2 is a lower-front perspective view of the ornamental
design for an entire configuration for an actuatable holding
system according to the invention, with the arms shown in an
opened position.

FIG. 3 is a front view thereof, with the rear view being
identical; and,

FIG. 4 is a left side view thereof, with the right side view being
identical.

The structures depicted by means of broken lines in the
figures have been shown for illustrative purposes only and form
no part of the claimed design.
